BOW TIE HANGER

William R. Howe, 4935 S. Delaware, Englewood, Colo.

Filed Feb. 6, 1962, Ser. No. 68,683

Term of patent 14 years

(Cl. D80—8)

FIG. 1.

FIG. 2.

FIG. 3.

FIG. 4.

FIG. 1 is a front elevation of a bow tie hanger showing my new design, the rear being substantially the same as the front shown;

FIG. 2 is a side elevation thereof;

FIG. 3 is a top plan view thereof, and

FIG. 4 is a bottom plan view thereof.

I claim:

The ornamental design for a bow tie hanger, as shown and described.
